PROTECTIVE MAKE-UP HOOD

Lillian L. Gettinger, 2509 Shelley Dale Drive,
Baltimore, Md.

Filed Apr. 7, 1965, Ser. No. 84,665

Term of patent 14 years

(Cl. D3—13)

FIG. 1

FIGURE 1 is a three quarter side perspective view of a protective make-up hood, showing my new design; and,

The portion of the protective make-up hood not shown continues as indicated being plain and unornamented.

I claim:

The ornamental design for a protective make-up hood, as shown and described.
